UNITED STATES PATENT OFFICE.

MAX LOBL AND ROBERT STEINBERGER, OF NEW YORK, N. Y.

DESIGN FOR ORNAMENTATION OF GLOVES.

60,552.

Specification for Design.

Patented Mar. 7, 1922.

Application filed September 22, 1921. Serial No. 502,576. Term of patent 3½ years.

To all whom it may concern:

Be it known that we, MAX LOBL and ROBERT STEINBERGER, citizens of the United States, residing in the city, county, and State of New York, have invented a new, original, and ornamental Design for the Ornamentation of Gloves, of which the following is a specification, reference being had to the accompanying drawing, forming part thereof, in which—

The figure shown is a plan view of a portion of a glove, embodying our new design.

We claim:

The ornamental design for the ornamentation of gloves, as shown.

MAX LOBL.
ROBERT STEINBERGER.
